CLAIM

The ornamental design for an aim enhancing system, as shown and described.

DESCRIPTION

FIG. 1 is a right side perspective view of an aim enhancing system.

FIG. 2 is a left side perspective view of the aim enhancing system of FIG. 1.

FIG. 3 is a front elevation view of the aim enhancing system of FIG. 1.

FIG. 4 is a back elevation view of the aim enhancing system of FIG. 1.

FIG. 5 is a top side view of the aim enhancing system of FIG. 1.

FIG. 6 is a bottom side view of the aim enhancing system of FIG. 1.

FIG. 7 is a right side view of the aim enhancing system of FIG. 1; and,

FIG. 8 is a left side view of the aim enhancing system of FIG. 1.

The broken lines form no part of the claimed design. The claimed design extends to the broken line boundaries but does not include the boundaries or the areas within the boundaries.

1 Claim, 6 Drawing Sheets
